Des. 191,633
Patented Oct. 24, 1961

191,633

GRILLE

Edward C. Hallock, 86 Woodlane Ave., Summit, N.J.

Filed Sept. 28, 1960, Ser. No. 62,286

Term of patent 14 years

(Cl. D54—2)

FIG. 1.

FIG. 2.

FIG.3.

I claim:

The ornamental design for a grille, as shown.
